Application June 2, 1950, Serial No. 10,314

Term of patent 14 years

(Cl. D22—3)

To all whom it may concern:

Be it known that we, Eugene J. Berger and Ernest Klein, respectively, a citizen of the United States, residing at 1472 Broadway, New York, New York, and a citizen of the United States, residing at 1265 47th Street, Brooklyn, New York, have invented a new, original, and ornamental Design for a Combined Knife, Saw and Fork, of which the following is a specification, reference being had to the accompanying drawing, constituting a part hereof.

Fig. 1 is a perspective view of the combined knife, saw and fork, showing our new design.

Fig. 2 is a side elevational view.

Fig. 3 is a side face view.

Fig. 4 is a cross-sectional view taken on line 4—4 of Fig. 3.

The dominant features of the design reside in the portions shown in full lines.

We claim:

The ornamental design for a combined knife, saw and fork, substantially as shown and described.

EUGENE J. BERGER.
ERNEST KLEIN.
